UNITED STATES PATENT OFFICE.

EDWARD E. GARLITS, OF TURTLE CREEK, PENNSYLVANIA.

IRON.

1,319,524.

Specification of Letters Patent. Patented Oct. 21, 1919.

Application filed June 3, 1919. Serial No. 301,504.

To all whom it may concern:

Be it known that I, EDWARD E. GARLITS, a citizen of the United States, and a resident of Turtle Creek, in the county of Allegheny and State of Pennsylvania, have invented a new and useful Improvement in Irons, of which the following is a specification.

My invention relates to electrically heated sad irons and particularly to double pointed irons.

One object of my invention is to provide an electrically heated sad iron that shall have reinforced terminal members forming an integral part of the heating element.

Another object of my invention is to provide an electrically heated sad iron that may be easily taken apart and re-assembled.

Another object of my invention is to provide a sheet metal unitary terminal member that shall be strong and durable in construction.

Another object of my invention is to provide a positioning member that shall be adapted to so hold the terminal members in position that they need not be secured to the hood of the iron.

A further object of my invention is to provide an iron, of the above indicated character, that shall be simple and inexpensive to construct and that shall have its terminal members so disposed as to insure uniform heating throughout and yet cause the leading-in terminals to be so placed at one side of the handle as to impose as little obstruction to the proper manipulation of the iron as possible.

In practising my invention, I provide a double pointed base or bottom plate, a unitary heating element having a uniformly distributed winding and unitary terminal members that extend from the center of the heating element, a top plate having an opening therein to permit the terminal members to extend to one side of the iron, a hood member and means disposed between the hood and the top plate for so positioning the terminal members as to retain the same in position without securing them to the hood. With this arrangement, the heating

element may be quickly replaced by the simple operation of removing the hood and the top plate.

In the accompanying drawings, Figure 1 is a sectional view of a sad iron embodying my invention; Fig. 2 is a top plan view with parts broken away of the top plate of the iron shown in Fig. 1 and Fig. 3 is a top plan view of the heating element shown in Figs. 1 and 2.

An iron embodying my invention comprises, in general, a double pointed bottom plate 1, a unitary double pointed heating element 2, a top plate 3, a hood 4, a guide socket 5 for the terminals of the iron and a handle member 6.

The unitary heating element 2, comprises a metal bottom sheath 7, a layer 8 of insulating material, a winding 9 that is uniformly distributed throughout to insure uniform distribution of heat, a second layer 10 of insulating material, two plates 11 and 12 having portions thereof cut away and so formed as to constitute receptacles 13 and 14, a layer 28 of insulating material and a top sheath 29. The conductors 15 from the winding 9 are secured to the plates 11 and 12 and the plates 11 and 12 are insulated from the bottom sheath 7 the edges of which are bent over to so retain the elements 7, 8, 9, 10, 11, 12, 13, 14, 28 and 29 in position as to constitute a unitary structure.

Threaded nipples 16 are secured in the receptacles 13 and 14 and receive threaded removable bayonet contact members 17. The portions 13 and 14 extend from substantially the center of the element 2 and are so shaped that they pass through an opening 18 in the top plate 3 of the iron. The opening 18 extends from substantially the center of the iron to one side thereof. Since the winding 9 is uniformly distributed and the opening 18 extends from a central portion of the member 19, the iron will be uniformly heated and will thus have no cold spots. Portions of the layer 28 of insulating material are bent upwardly to protect the members 13 and 14 as they pass through the opening 18.

Screws 20 are provided for securing the

element 2 and the top plate 19 to the base plate 1 and screws 21 are provided for securing the hood 4 of the iron in position. The screws 21 are also adapted to secure the 5 saddle member 23 and the guide socket 5 in position. The handle 6 is secured to the saddle member 23 by a bolt or pin 24.

An insulating member 25 having a shoulder 26 at one end to engage the opening in 10 the hood 4 and an internal shoulder 27 to fit over the receptacles 13 and 14 is disposed around the members 13, 14 and 17 and is so clamped between the top plate 3 and the hood 4 as to effectively support the members 15 17 and to prevent withdrawing the same to break the lead conductors to the winding 9 when the iron is disconnected by removing the plug connector (not shown).

From the above, it will be seen that it is 20 unnecessary to secure the members 17 to the hood and thus the iron may be easily taken apart and the members 17 may be replaced without taking the iron apart. In order to renew a heating element, it is only necessary to remove the screws 20 and 21. This 25 permits the hood 4, and top plate 19 to be removed and a new heating element inserted. Since the members 17 are disposed at one side of the handle 6 intermediate the 30 legs of the saddle 23, it will be seen that one of the chief difficulties of double pointed irons is removed. That is, the connecting cord is at one side and, consequently, out of the way. Heretofore, this was not feasible 35 because if the terminals were brought through the top plate at one side, less material would obtain at that side and thus result in cold spots. By my improved construction, since the terminals are brought 40 from the center of the iron, the heat is distributed uniformly.

My invention is not limited to the specific structure illustrated, as various modifications may be made therein within the spirit 45 and scope of the invention, as set forth in the appended claims.

I claim as my invention:

1. In an electrically heated sad iron, the combination with a double-pointed bottom 50 plate, of a double-pointed heating element having its windings evenly distributed, and a top plate having an opening therein extending from the central portion of the bottom thereof to a side portion of the top to 55 permit the leads to the heating element to pass therethrough.

2. In an electrically heated said iron, the combination with a double-pointed bottom plate, a double-pointed heating element, a 60 top plate, and a hood member, of terminal members for the heating element integral therewith and passing through the top plate to a position adjacent the hood member, and a bushing disposed between the hood mem-

ber and the top plate to secure the terminal 65 members in position.

3. In an electrically heated sad iron, the combination with a double-pointed bottom plate, a double-pointed heating element, a top plate, and a hood member, of terminal 70 members for the heating element integral therewith and passing through the top plate to the hood member, and a removable insulating bushing disposed around the terminal members between the hood member and 75 the top plate.

4. In an electrically heated said iron, the combination with a bottom plate, a heating element, a top plate, and a hood member, of terminal members for the heating element 80 integral therewith and passing through the top plate, bayonet contact members secured to the terminal members, and means disposed around the terminal and the bayonet members and wedged between the hood and the top plate for securing the said members in position with respect to the hood member where they pass through the top plate. 85

5. In an electrically heated sad iron, the combination with a bottom plate, a heating element, a top plate, and a hood member, of a terminal member for the heating element integral therewith and passing through the top plate to one side of the hood member, and a removable insulating member so 90 wedged between the hood member and the top plate as to secure the terminal member 95 in position.

6. A heating element for a sad iron comprising a terminal plate having portions thereof formed to constitute a receptacle, an internally-threaded member disposed in the receptacle so formed and a bayonet contact member disposed in the threaded member. 100

7. A heating element for a sad iron comprising a terminal plate having portions thereof formed to constitute a receptacle, an internally-threaded member disposed in the receptacle so formed and a screw-threaded bayonet contact member disposed in the 105 threaded member.

8. A heating element for a sad iron comprising a terminal plate having integral portions thereof formed to constitute a tubular member, and a contact member removably disposed in the tubular member. 115

9. In an electrically heated sad iron, the combination with a double-pointed bottom plate, of a double-pointed unitary heating element having its terminals at the center thereof, a uniformly distributed winding and a top plate having an opening therein to permit the terminals from the center of the heating element to pass therethrough to a 120 position to one side thereof.

10. In an electrically heated sad iron, the combination with a double-pointed bottom plate, a double-pointed heating element, and 125

a handle, of a top-plate and a hood to permit the terminals of the heating element to extend from the center of the heating element to a position at one side of the handle.

5 11. In an electrically heated sad iron, the combination with a heating element, a top plate and a hood, of terminal members integral with the heating element and extending freely through the top plate and the
10 hood, and freely removable means wedged

between the hood and the top plate for securing the terminal members in position.

12. In an electrically heated sad iron, the combination with a double-pointed base plate, of a double-pointed heating element 15 having its terminals at the center thereof.

In testimony whereof, I have hereunto subscribed my name this 2nd day of June, 1919.

EDWARD E. GARLITS.
